(57) **CLAIM**

The ornamental design for multi-function clip, as shown and described.

DESCRIPTION

FIG. 1 is a right side perspective view of multi-function clip showing my new design;

FIG. 2 is a left side perspective view thereof;

FIG. 3 is a front elevational view thereof;

FIG. 4 is a left side elevational view thereof;

FIG. 5 is a top plan view thereof;

FIG. 6 is a right side elevational view thereof;

FIG. 7 is a rear elevational view thereof; and,

FIG. 8 is a bottom plan view thereof.

The broken line showing of a pen is included for the purpose of illustrating environment and forms no part of the claimed design.
